UNITED STATES PATENT OFFICE

2,197,926

LIFT TRUCK

Elmer J. Dunham, Battle Creek, Mich., assignor
to Clark Equipment Company, Buchanan,
Mich., a corporation of Michigan

Application August 8, 1936, Serial No. 94,926

7 Claims. (Cl. 254—10)

This invention relates to lift trucks, and more particularly is directed to improvements in the construction and operation of lift trucks of the type disclosed in United States Letters Patent 5 Nos. 1,707,428 and 1,986,134, issued April 2, 1929, and January 1, 1935, respectively, to Robert J. Burrows, and to Burrows and Williams.

The invention is primarily concerned with self-propelled lift trucks such as are now commonly 10 used in warehouses, manufacturing plants, wharves, and the like to lift and transport heavy loads of merchandise and stock about the premises.

Trucks of this class are usually either of the 15 electric motor propulsion type, deriving their energy from storage batteries, or internal combustion engine propulsion type, similar in some respects to a tractor. In the instant case, the invention is directed to the internal combustion 20 engine type of truck, and primarily contemplates certain improvements and modifications in design and construction that will facilitate easy and quiet operation of the truck under all conditions.

The present invention has for its primary object 25 a design of lift truck that will meet the demands of the industry for a heavy-duty low-lift truck with sufficient power to meet all ordinary operating conditions and with full load ramp characteristics on ramps ordinarily encountered in industrial plants.

One object of the present invention is to provide 30 a truck of this type having two speeds forward and two speeds reverse, all driven through constantly meshed gears controlled by clutches to eliminate any possible clashing of gears. By the provision of a novel gear shifting arrangement, forward and reverse speeds can be selected only when in neutral driving position, and no change can be made during driving of the truck. 35 The provision for two speeds is highly desirable in plants where long hauls are made, and the truck is then capable of returning empty at high speed. The low speed is used on ramps and in congested operating locations, such as aisles in 40 shops and warehouses, where a higher speed is both impractical and undesirable.

Another feature of the present invention is the 45 novel design of steering mechanism employed when a six wheel truck for heavy loads is provided. In such a construction, I provide a six-wheel machine in which all of the wheels act as steering wheels when a turn is to be made. The front wheel suspension consists of four wheels 50 which are so mounted as to impart great flexibility

to the machine, and to relieve the frame of the machine from any severe strains when passing over uneven road surfaces. Each set of wheels is independent as the front and rear wheels of the four-wheeled front truck on each side of the frame are mounted on a single rocker arm which is pivoted to the frame intermediate the wheels. Thus all four wheels remain in contact when the machine passes over uneven floors, which greatly assists in proper weight distribution and substantially equalizes tire wear.

Another feature of the present invention resides in the hydraulic system used for controlling lifting and lowering of the load platform. In the present invention, this comprises a pump 15 driven directly from the internal combustion engine and connected through flexible pipes to a balanced slide valve mounted on the lift cylinder. The piston rod in the cylinder has a straight gear rack on its outer end which engages a fan-shaped gear segment connected through a shaft directly to the levers and linkage which raises the load. The pump has been especially designed for the type of service encountered and is mounted directly on the transmission case, thus eliminating any misalignment which might be occasioned by couplings or the like. Preferably, I employ double lift cylinders in order to equalize the lift on opposite sides of the platform, and utilize a simplified system of interconnection between the lift cylinders so that only a single control valve is required. The mechanism which controls operation of the valve is automatically returned to neutral position when the platform reaches the upper and lower limits of movement 30 so that no possibility of over-stressing the raising and lowering mechanism is produced.

In order to simplify the control of the truck, I have provided a single lever which controls forward and reverse engagement of the gears, and also controls the main drive clutch and the throttle control for the engine. This lever is mounted for easy operation on the dash board of the vehicle and is so arranged that the main clutch must be disengaged before selection of forward or reverse speeds can be obtained.

Still another object of the present invention is the provision of a novel drive connection between the engine and the driving axle, this connection including a four-pinion differential especially designed for industrial trucks and driven from a double-reduction spur and bevel gear driving arrangement.

The entire truck design has been developed with particular attention to the accessibility of all 55

of the parts for servicing and simplicity of design of the majority of parts so that they are capable of economical development.

Other features and advantages of the present truck construction will be more apparent from the following detailed description, which, taken in conjunction with the accompanying drawings will disclose to those skilled in the art the particular details of construction and operation of a preferred form of the present invention.

In the drawings:

Figure 1 is a perspective view of the truck with the platform in lowered position;

Figure 2 is an end elevational view of the truck showing the operator's platform;

Figure 3 is a detailed perspective view showing the control mechanism for controlling the various driving and lifting operations of the truck;

Figure 4 is a sectional view through the transmission showing the clutching arrangements for controlling selection of the various speeds of operation;

Figure 5 is a sectional view through the driving connection between the transmission and the differential on the driving axle, and also showing details of the brake construction;

Figure 6 is a sectional view through a portion of the driving axle;

Figure 7 is a sectional view showing the connection between the oil pump and the transmission;

Figure 8 is a side elevational view of the lift lever control;

Figure 9 is an end elevational view of the mechanism shown in Figure 8;

Figure 10 is a top view of the mechanism shown in Figure 8;

Figure 11 is a side elevational view of the main control lever mechanism;

Figure 12 is a top view of the same mechanism;

Figure 12A is a front elevational view of the plate frame for the lever;

Figure 13 shows in detail the lift cylinder and platform control;

Figure 14 is a section taken substantially on line 14-14 of Figure 16;

Figure 15 is a figure taken substantially on line 15-15 of Figure 16;

Figure 16 is an end elevational view of the lift valve construction;

Figure 17 is a perspective view showing the front truck mounting for the steering wheels;

Figure 18 is a diagrammatic view showing the steering mechanism for a four-wheeled truck;

Figure 19 is a diagrammatic illustration of the steering linkage for a six-wheeled truck; and

Figure 20 is a perspective view showing the arrangement of the lift cylinders and the end construction of the transmission unit.

Referring now in detail to the drawings, and more particularly to Figures 1 and 2, the lift truck is indicated generally by the numeral 5 and comprises a load platform 6 mounted over a front wheel truck assembly indicated at 7, and adapted to be raised and lowered by rotation of the arms 8 connected to the under side of the platform and controlled by movement of the piston within the lift cylinder 9, as described in detail in the above mentioned patents.

The engine for the truck is mounted beneath the hood 10, which is formed in two sections 11 and 12, the section 11 being hinged at 13 so that it can be opened for inspection and servicing of the engine, and being held in closed position by the overhanging clamps 14 carried by the upright

control panel 15 extending vertically at the forward end of the engine. Suitable side plates 16 enclose the sides of the engine and the operating mechanism and protect the mechanism from mechanical injury. The operator's platform is indicated at 18 and is preferably rounded in order to eliminate any sharp corners so that the truck can readily be maneuvered in narrow aisles. Similarly, the forward end of the truck is tapered for maneuvering about sharp corners, and to prevent cornerwise abutment. The main drive wheels, resiliently tired, are indicated at 19 and are mounted beneath the engine and forwardly of the operator's platform 18.

Referring more particularly to Figure 2, the control panel is provided with a suitable opening through which extends the radiator 20 for the engine of the truck, the radiator being mounted in suitable supporting members 22 and having protecting guard strips 23 over the outer face thereof. An inlet for the radiator is indicated at 24 and a suitable drain cock is provided at 25 shown in Figure 1, as is the customary practice. The vehicle is steered by means of the hand wheel 26 mounted on a horizontal axis and adapted to be rotated by the operator standing on the platform 18. Through suitable gear means, the rotation of the hand wheel effects corresponding rotation of the shaft 27 to cooperate the steering mechanism, which will be described in more detail in connection with Figures 19 and 20.

The operator's platform 18 is preferably covered with a sponge rubber matting 28 for cushioning the operator against any bumping or vibration of the vehicle, and is provided with the brake pedal 29 which is normally urged into brake-setting position and must be moved downwardly into a position flush with the platform in order to effect release of the band brake members 30 and 32 appearing in the cut-out portion of the panel 15 indicated at 33 in Figure 2. A suitable starter button 34 is provided to eliminate hand cranking of the engine since this has been found undesirable and safety requirements demand that automatic starting be provided. An instrument housing 35 is mounted below the steering wheel 26 and preferably contains an ammeter 36 indicating the condition of the battery, and any other suitable instruments, such as the horn button 37.

At the right hand side of the control panel 15 and adjacent the top thereof, is a gear shift member 38 which extends forwardly through the panel and is movable toward and away from the panel to effect shifting of the drive from low to high speed. Directly below the member 38 is the frame plate 39 which is suitably apertured to receive the outwardly extending main control lever 40. This lever, as will be described in more detail hereinafter, controls operation of the main driving clutch and also controls selection of forward and reverse driving connections, being movable sideways in its lowermost position to effect selection of direction of drive and movable vertically to engage the main driving clutch.

To the right of the frame plate 39 and lever 40 is a second frame plate 43 which forms an opening for the lift control lever 44 which, when raised to its upper position in the slot 45, effects lowering of the lift platform 6, and when moved downwardly from the neutral position in which it is shown, effects raising of the platform.

Considering now in detail Figure 3, which shows the larger portion of the operating mechanism for the truck, the engine is indicated generally at 48. The engine is cooled from the ra-

- diator 20 through the usual radiator connections, one of these being shown at 49 leading from the top of the cylinder block to the header 50. The fuel for the engine is supplied through the carburetor 52 which has the air inlet 53 connected to atmosphere through the air cleaner 54. The fuel supply tank 55 is mounted on the top of the transmission housing 56, and the inlet 57 thereof is protected by the sealing closure 58.

5 The engine is preferably a standard automotive engine, especially adapted for this type of work and may be, for example, a six-cylinder engine having governor means which controls its maximum speed of operation. The engine 10 fan 59 is driven from a pulley on the crank shaft of the engine through the fan belt 60, which also drives a suitable pulley 62 for driving the generator 63. A suitable distributor of any standard 15 type is indicated at 64 and has the leads 65 connected to the various spark plugs for the engine cylinders. The engine is supported upon the side frame members 66 by means of the supporting brackets 67, these side frame members 20 extending forwardly as indicated at 68 to provide support for the transmission housing 56. The panel 15 is supported and braced from the transmission housing 56 by means of the tie rods 69 secured to suitable brackets 70 bolted to the housing. The oil inlet for the engine crank case 25 is indicated at 72 and is provided with the usual type of breather cap 73.

30 The housing which receives the shaft rotated by the steering wheel 26 is indicated at 74 and is suitably bolted to the inner face of the panel 35 15, the vertical steering shaft 27 extending upwardly into the housing 74 and being geared to the shaft of the steering wheel in a manner similar to the connection at the lower end of the steering wheel of an automotive vehicle.

40 An oil reservoir is provided at 75, and is supported in any suitable manner on the engine, having the T connection 76 at its lower end provided with the inlet 77 connected to the flexible pipe 78 leading from the exhaust outlet of 45 the valve housing 79, and having an outlet connection 80 communicating with the oil pump chamber 82. From the chamber 82 an outlet connection 83 is provided leading through the flexible pipe 84 to the inlet 85 of the lift-control 50 valve housing 79. This housing is mounted in suitable manner upon the top of the pump cylinder 9 and controls operation of the pump.

55 The oil supply for the pump cylinder is separate and independent of the oil supply for the crank case of the engine, the crank case oil being connected to the usual oil filter 86 in a well known manner. For the sake of convenience, the horn controlled by the horn button 37 is mounted on the top of the engine adjacent the 60 forward end thereof, and is indicated at 87.

65 Referring now to Figure 4 which is a vertical sectional view through the transmission unit, the housing 56, which, at its forward end is provided with the flange 89 adapted to be bolted to the rear of the engine block 88, is provided at its top with an opening 90 for access to the interior of the housing, this opening being closed by a suitable plate 92 bolted thereto at its forward end. The housing has a suitable opening 65 which receives the enlarged end 93 of the driving shaft. This end has the flange portion 94 adapted to receive the flywheel member 95, which is suitably centered and bolted rigidly thereto. The flywheel 95 has a central opening which receives 70 the ball-bearing assembly 96 in which the inner 75 end 97 of the main clutch shaft 98 is journaled. At its outer periphery, the member 95 is provided with a shouldered face 99 to which is bolted the outer clutch casing 100. The clutch assembly, indicated generally at 102, is of the multiple disc type and is of ample capacity to take the full motor torque. The inner clutch member 103 is keyed to the forward portion of the driven shaft 98, as indicated at 104, and is held in position by means of the spacing sleeve 105 and the lock nut 106 threaded onto the end of the shaft 98 and forcing the sleeve 105 against the shoulder 107 of the shaft.

Extending radially about the outer periphery of the member 95 is a ring gear 108 which is adapted to have meshing engagement with any suitable type of starting gear for cranking the engine. A second suitable ring gear 109 is riveted to the side face of the plate 95 and is adapted to have driving engagement with suitable gear means connected to the oil pump mechanism to be described hereinafter.

A suitable double spring 110 is disposed between the member 103 and the thrust plate 112, and normally urges the clutch out of clutching engagement. To engage the clutch, a thrust bearing 113 is provided with a shoulder adapted to engage the outer face of the thrust member 112 and which is moved into pressure engagement therewith by means of the clutch sleeve 114 having oppositely extending arms 115 adapted to be engaged by a suitable clutch yoke for movement to the left to force the member 112 inwardly to effect clutching engagement between the members 100 and 103, directly clutching the shaft 98 to the engine flywheel plate 95.

The clutch yoke is actuated by means of the rock shaft 116 extending outwardly of the housing 56, as shown in Figure 3, and having the arm 117 keyed thereto. Connected to the arm 117 is the yoke member 118 which, through the tie rod 119, is connected to a second yoke member 120 carried by the rock arm 122 mounted on the shaft 123 to which the lever 42 is keyed for rocking the shaft upon vertical movement of the lever. This in turn rocks the arm 122 to effect longitudinal movement of the rod 119 for rocking the shaft 116 to engage and disengage the clutch.

The clutch member 114 is slidably mounted on the hub of the gear member 125, which is 50 freely rotatable about the shaft 98 on the roller bearings 126. The member 125 has the external helical gear portion 127 and the internal clutch tooth portion 128. A second gear member 129 is also mounted on the shaft 98 by means of the roller bearings 130, and is held against movement outwardly of the shaft by means of the plate 132 bolted to the end of the shaft. The gear 129 is suitable journaled in the end of the housing 56 by means of the ball-bearing assembly 133, the outer race of the assembly being locked in position by means of the cap plate 134 threaded in the bearing ring 135 which is bolted in the end face of the housing. The inner race of the assembly 133 is locked between the shoulder on the gear 129 and the end plate 132. The gear 129 has the outer helical gear portion 136 and the internal clutch tooth portion 137. The shaft 98 between the gears 125 and 129 is splined, as indicated at 138, and receives a suitable clutch sleeve 139 having the clutch tooth portions 140 and 142 which have clutching engagement with the teeth 128 and 137, respectively, upon axial movement of the member 139. The clutch sleeve 143 is provided with a groove 144 adapted to receive

a clutch yoke for moving it along the splines 138 into and out of clutching engagement with the respective gear members 125 and 129.

- The clutch yoke is mounted on a sleeve which 5 extends outwardly of the housing 56 and is keyed to the hub 144 of a rocker arm 145 which, at its outer end, is connected through the yoke 146 to the tie rod 147 connected at its opposite end through the yoke 148 to the speed control member 38 which projects through the panel 15 and, upon upward movement, rocks the arm 145 in a counterclockwise direction to move the clutch 139 into engagement with the gear 125 to effect low speed driving engagement of the transmission. Upon moving the member 38 inwardly with respect to the upright, the arm 145 is rocked in a counterclockwise direction to engage the clutch 139 with the gear 129 to effect high speed driving engagement of the transmission.
- 20 Disposed beneath the shaft 98 is a second shaft 150 which forms a countershaft journaled in the bearing assemblies 152 and 153. Bearing assembly 152 is carried by an upstanding journaled flange 154 formed integral with the housing 56.
- 25 The shaft 150 is provided at its ends with lock nuts 155 preventing axial movement thereof in the bearings 152 and 153. A gear 156 keyed to the shaft at 157 is adapted to have meshing engagement with the gear 125 and is driven thereby 30 when the clutch 139 is moved into clutching engagement with the gear 125. A second gear 158 is keyed to the shaft 150 at 159 and has driving engagement with the gear 129. A suitable spacing sleeve 160 is disposed between the gears 156 35 and 158, and serves to maintain these gears in proper driving position with respect to the gears 125 and 129. A suitable cap plate 162 is secured to the end face of the housing 56 and closes the end of the shaft 150. Low speed driving engagement of the clutch 139 provides for driving of a 40 countershaft 150 from the flywheel 95 through the gears 125 and 156. High speed driving engagement is effected through the gears 129 and 158.
- 45 Disposed below the shaft 150 is the main driven shaft 165 which has a gear 166 mounted thereon by means of roller bearings 167. The gear 166 is journaled for rotation with respect to the housing by means of the bearing assembly 167 retained in position by the closure plate 168 bolted to the forward face of the housing. The shaft 165 also carries the gear 169 mounted thereon by roller bearings 170 and held against axial movement by means of the thrust washer 172 50 and the end plate 173 bolted to the end of the shaft. The gear 169 is journaled in the housing by means of the bearings 174 which are held in position by the closure plate 175 bolted to the rear face of the housing 56.
- 55 Intermediately the bearings 167 and 170, the shaft 165 is splined, as indicated at 176, which is adapted to receive the clutch collar 177 which is axially movable thereon. Each of the gears 166 and 169 has corresponding internal clutch tooth portions 178 and 179, respectively, which are engaged by corresponding clutch portions 180 and 182 of the clutch collar 177. The collar 177 is provided with an intermediate annular groove 183 receiving the ears 184 of a clutch yoke 70 185 carried on the rock shaft 186. The rock shaft 186 projects outwardly of the housing 56 through the sleeve which is keyed to the hub 144 of the arm 145. Clamped to the outer end of the shaft 186 is a rock arm 187 which, at its extending end, is connected to the yoke 188 that

has coupling engagement through the rod 189 with the yoke 190 connected to the arm 192 carried at the lower end of the shaft 193 that extends vertically upwardly and is journaled at its upper end in the bracket 194 forming part of the frame plate 39. At its lower end the shaft 193 is journaled in a bracket 195 bolted to the rear face of the upright 15.

The shaft 193 at its upper end has keyed there-to the arcuate segment 196 which, at its upper 10 end, is journaled to a stub shaft also carried by the upper portion 197 of the bracket 194. The arcuate segment 196 has a longitudinal slot 198 therein which receives the extending tongue portion 199 of the control lever 42. The control lever 15 42 is pivoted for lateral swinging movement about a stub shaft 200 carried in a bracket 202 formed integral with the shaft 123 whereby the lever 42 has substantially universal pivotal mounting due to its rocking movement on the shaft 123 20 for vertical movement, and is pivotally mounted on the stub shaft 200 for lateral swinging movement with respect to the shaft 123 regardless of its angular position. Thus, when the lever 42 is rotated in a clockwise direction about the stub 25 shaft 200, the tongue 199 engaging the sides of the slot 198 rotates the arcuate segment 196 in a clockwise direction and thus effects clockwise rotation of the shaft 193. This results in angular movement of the end of the arm 192 producing longitudinal movement of the rod 189 to the right as shown in Figure 3, and thereby producing counterclockwise movement of the arm 187 to move the clutch collar 177 into clutching engagement with the gear 169. Between the gear 169 and the gear 158, there is provided an intermediate gear mounted on a reverse idler shaft disposed laterally outwardly of the plane of the shafts 150 and 165 and journaled in the bearing cap 208. This effects reverse rotation of the 30 shaft 165 to provide for reverse drive of the vehicle.

Since either the gear 156 or 158 can rotate the countershaft 150, it is obvious that reverse drive in both low and high speeds is accomplished when 35 the clutch collar 177 is shifted to clutch the gear 169 to the shaft 165. When the lever 42 is rotated in a counterclockwise direction, it effects corresponding rotation of the segment 196 which in turn, through the shaft 193 and tie rod 189, effects clockwise rotation of the shaft 186, thereby clutching the gear 166 to the shaft 165 and thus produces forward drive regardless of the position of the clutch member 139. Thus, forward and reverse drives in either of the two 40 speeds are provided.

The outer projecting end 210 of the shaft 165 is keyed into the hub portion 212 of a universal coupling yoke 213 which has coupling engagement with the corresponding yoke 214, completing 45 the universal coupling.

Referring now in detail to Figure 5 which shows the extension of the drive from the transmission unit to the axle, the universal coupling comprising the yoke members 213 and 214 couples 50 the shaft 165 to the propeller shaft 215 which extends through the upper portion of the differential housing 216. The housing 216 is provided with a journaled portion 217 carrying the tapered roller bearings 218 for journaling the 55 shaft 215 for rotation therein. The extending end 219 of the shaft is keyed to the yoke 214 as indicated at 220. A suitable closure plate 222 holds the bearing assembly 218 in position and engages about the hub portion of the yoke 214. 60 75

Suitable oil sealing means 223 is disposed in the recessed portion of the plate 222.

The shaft 215 at its opposite end is provided with a reduced portion 224 which receives the 5 brake drum 225 keyed thereto as shown at 226. The shaft 224 is journaled in a rear extension 227 of the differential housing by means of bearings 228, these bearings being locked into position by the plate 229 carrying the oil sealing 10 means 230.

The extension 227 of the housing 216 provides a support for a suitable bracket 232 which carries the brake band pivot members 233 supporting the brake bands 30 and 32 for engagement 15 with the drum 225. This brake is of the usual type of external band brake having the free ends thereof provided with brackets 234 as shown in Figure 6 normally urged together by the relatively heavy coiled spring 235 carried by the 20 differential housing and a crank arm 240 is keyed to the shaft to effect rotation of the wedge through bolt 236 extending between the brackets. A suitable spreading wedge 237 is carried upon a stub shaft 238 supported in the bracket 239 secured to the rear face of the extension of the 25 differential housing and a crank arm 240 is keyed to the shaft to effect rotation of the wedge for spreading the brackets 234 apart against the spring pressure to release the brake. The crank arm 240 is connected in any suitable manner to the shaft which is rotated by depression of the 30 brake pedal 29.

Intermediate the journal bearings 228 and the differential housing 216, the shaft 215 is provided with a gear portion 242 which has meshing engagement with a gear 243 keyed at 244 to the 35 pinion shaft 245 extending from the rear of the differential casing 216 into the axle casing and having the drive pinion 246 at the inner end thereof. The shaft 245 is suitably supported in double tapered roller bearings indicated generally at 247 which are held in position by the bearing retaining member 248 clamped to the closure plate 249 and fitting in the journal opening in the rear extension of the housing 216. At its inner end, the shaft 245 is journaled in 40 the roller bearings 250 carried by the housing 216. It will thus be apparent that a double-reduction drive is effected between the engine and the drive axle regardless of the position of the clutch 139, the first reduction being effected 45 by the gears 242 and 243 and the second reduction being effected between the drive pinion 246 and the bevel ring gear 252 shown in Figure 6.

The ring gear 252 is bolted to a differential casing 253 of the four-pinion type, which receives the stub axle shafts 254. The shafts 254 extend through suitable housing members 255 bolted to the sides of the differential housing 216 and at their outer ends are adapted for splined drive connection with the hub 257 of one yoke 258 of a universal driving coupling indicated generally at 259. From the coupling 259, the drive extends through the stub shaft 260 to the driving member 262 bolted to the hub portion 263 of the wheel 19.

The hub 263 of the wheel 19 is journaled for rotation by means of the tapered roller bearings 264 on the cylindrical portion 265 of a spindle bearing member 266 which has the oppositely extending spindles 267 thereof journaled for rotation 5 in the spindle bracket 268 by means of the bearings 269 and 270. The bracket 268 is bolted to the outer face of the housing member 255 and provides for dirigible mounting of the wheel 19 in order to assist in steering the vehicle. It is to be understood that the differential 253 has two

axle spindles 254 extending in opposite directions and that the wheels 19 are driven therefrom through the coupling 259 and the driving member 262, each of the wheels being spindle-mounted for steering movement.

The axle assembly is supported from the frame of the truck by means of leaf spring members 272 extending beneath the housing members 255 and retained by the U-shaped spring yokes 273. The springs 272 at their ends are mounted in suitable shackles 274 bolted to the supporting side frame members 66. By reason of the universal coupling 213, 214, relative movement of the axle assembly with respect to the frame of the truck is accommodated, when the vehicle is being driven over uneven road surfaces. The universal 10 couplings 259 intermediate the ends of the axles allow steering movement of the wheels 19 without interfering with the driving torque transmitted thereto from the differential 253.

It is to be pointed out that the driving spindles are mounted in suitable bearing members 280 and 282 which journal the same with respect to the spindle bracket 266 and the housing 255, and take radial loads which may be produced in the 15 transmission of torque. If desired, the universal couplings may be of a design including rubber bushings in order to reduce noise and wear. The differential housing is sealed against leakage of oil or lubricant along the shaft 215 by means of 20 the oil sealing means 223 and the oil sealing means 283 carried by the closure plate 229. A suitable drain plug 284 is provided for removing and replenishing this lubricant.

It is to be noted that the housing 216 is made 25 up of two separate complementary cylindrical portions which are piloted together at 285 and are bolted in sealed engagement by the peripheral ring of bolts 286 extending through the abutting 30 radial flanges 287 and 288 of the complementary members forming the housing 216.

Referring now in detail to Figures 13 to 16, inclusive, directed to the details of the control valve for the pump or lift cylinder, the housing for the valve is provided with an end cap member 290 having the packing gland nut 292 threaded therein for sealing the external surface of the valve stem 293. The outer end of the valve stem is locked in a block member 294 pivotally mounted by links 295 on an arm 296 keyed to 40 the rock shaft 297.

The shaft 297 is supported in suitable journals carried by the bracket arms 298 formed integral with the plate 299 bolted to the end plate 300 of the cylinder 9. Also secured to the shaft 297 for 45 conjoint rotation therewith is the bell crank 302 having adjustable stops 303 and 304 carried at the opposite ends of the arms thereof. The vertical arm of the bell crank 302 is provided with an offset projecting lug 305 which is connected 50 through the yoke 306 to the longitudinally extending rod 307. At its opposite end, the rod 307 is connected through the yoke 308 to an arm 309 carried at one end of a horizontally extending shaft 310 journaled in the bracket 312 secured 55 to the upright 15. The opposite end of the shaft is provided with an arm 313 connected through the rod 314 to the shaft 315 upon which the lift lever 44 is pivoted, as will be described hereinafter.

The valve housing 79 is secured to the upper surface of the pump cylinder 9 by means of a plurality of bolts 320 and is aligned in position such that the passageways 322 and 324 are aligned respectively with passageways 325 and 75

326 formed in the upper part of the lift cylinder 9.

These passageways in turn communicate through ports 327 and 328, respectively, with opposite ends of the interior of the cylinder indicated generally at 330. The opposite end of the cylinder is closed by the head plate 329. Disposed for reciprocatory movement within the piston chamber is a piston member 332 having the cup leather 333 bolted thereto by peripheral ring of bolts 334. Threaded into the piston 332 is a piston rod 335 which extends outwardly through the packing gland formed by the socket portion 336 of the head plate 300 and the packing gland nut 337 threaded therein which holds the packing material 338 compressed upon the opposite sides of the metallic bushing 339. At its outer end the piston rod 335 is provided with a flattened portion 340 having rack teeth 342 thereon adapted to have meshing engagement with the gear segment 343 mounted on the shaft 344 extending transversely of the truck frame. The flattened part 340 of the piston rod is guided for movement by the bearing member 345 carried by the supporting bracket 346 secured to the side frame 347 forming a portion of the undercarriage of the platform. When the piston moves outwardly of the cylinder, the shaft 344 is rotated in a clockwise direction to lower the platform 6 while, when the shaft 344 is rotated in the opposite direction upon inward movement of the piston, the platform is raised through rock arms and toggle links of the same general construction as described in the aforesaid Burrows, and Burrows and Williams patents.

Considering now in detail the construction of the valve member indicated generally at 79, this member has an outlet port 348 to which is connected the flexible pipe 78 and which communicates within the housing 79 with the main outlet passageway 349 and with the normally extending passageways 350, 352 and 353. The housing 79 is also provided with a central axially extending cylindrical bore 354 which receives the slidable valve member indicated generally at 355 and preferably formed integral with the valve stem 293.

The end of the bore 354 is closed by the cap member 356 bolted to the face of the housing 79. At its top, the housing 79 is provided with a high pressure inlet port 357 communicating with the flexible pipe coupling 85 and having the main inlet passageway 358 and the normally extending auxiliary passageways 359, 360 and 362 communicating with the bore 354 of the valve housing. In both Figures 14 and 15 the valve is shown in its neutral position, in which position the enlarged cylindrical portions 363 and 364 close off the passageways 365 and 366 communicating with the ports 322 and 324.

When the valve is moved to the left as shown in Figures 14 and 15, the portion 364 moves into a position opening the passageway 366 and thereby provides communication from the inlet 357 through the passageways 358 and 359 and the reduced portion 367 of the valve to the passageway 366, and thence through the port 324 and the chamber 326 and port 328 to the left hand end of the lift cylinder. At the same time, the enlarged portion 363 of the valve also moves to the left, blocking the passageway 362 leading from the high pressure inlet 357 and opening the passageway 365 leading from the port 322 which is in communication through the passageway 325 with the righthand end of the pump

chamber. The passageway 365 under such conditions is in communication with the exhaust passageway 353 around the reduced portion 368 of the valve, and hence fluid from the right hand side of the piston 332 is exhausted into the conduit 78 and thence to the T connection 76. The passageway 352 at this time is in communication with the annular chamber 369 and exerts equal pressure against the enlarged flanges 370 and 372 of the valve, neutralizing any tendency of the valve to move from this position. At the same time, the high pressure passageway 360 exerts equal pressure against the face of the flange 372 and against the face of the enlarged portion 363 of the valve through the chamber 373 and the reduced portion 374 of the valve so that the valve tends to remain in the position to which it has been moved for lowering the platform.

When the valve is moved to the right by actuation of the lever 44 moving the rod 307 forwardly to rock the shaft 297 in a clockwise direction, the valve moves to a position where the enlarged portion 364 closes off communication between the passageway 366 and the passageway 359, and opens communication between the passageway 362 and the passageway 365. This delivers fluid under high pressure through the port 322 and the passageway 325 to the right hand end of the cylinder chamber to move the piston 332 to the left to raise the platform. At the same time, the enlarged portion 364 of the valve opens communication between the passageways 366 and 350 around the reduced portion 375 of the valve, thereby providing an outlet path through the passageway 350 to the outlet 348. This movement of the valve also effects closing of the communication between passageways 353 and 365 to prevent exhaust of fluid from the passageway 362 into the passageway 353, while allowing the fluid under high pressure to pass through the passageway 362 to the passageway 365. In addition, the enlarged flanges 370 and 372 of the valve are moved into position to close off the passageway 369 and to admit fluid under high pressure through the passageway 360 against the adjacent faces of these flanges to hold the valve in a balanced pressure position so that the fluid under high pressure will not tend to move it out of the position to which it has been shifted.

Both of the end flanges 355 and 376 of the valve are provided with vent openings 377 to prevent trapping of oil between the outer faces of these flanges and the ends of the bore 354. Suitable packing 378 is compressed in position about the external surface of the valve stem 293 by the packing gland nut 292 to prevent any leakage of oil outwardly along the valve stem.

It is thus apparent that upon pushing the lever 44 downwardly to rock the shaft 315 in a counterclockwise direction, the toggle links 380 and 382, shown in detail in Figures 8 to 10, rock the arm 383 in a counterclockwise direction whereby the shaft 384 is correspondingly rotated to move the rod 385 connected to the arm 386 carried by the shaft, forwardly of the vehicle. The rod 385 at its forward end is connected through the yoke 386 to the crank arm 387 mounted on the shaft 388 and rotates the shaft 388 in a clockwise direction to effect engagement of the pump clutch which will be described in detail hereinafter. As a result, the oil pump operates to pump oil under pressure through the conduit 84 to the high pressure inlet 357. At the same time the rod 314 is moved downwardly, which results in forward mo-

tion of the rod 307 and consequently moves the arm 296 in a clockwise direction to move the valve into platform raising position. Under such conditions, oil under pressure is transmitted from the inlet 357 through the passageways 358, 362, and past the reduced portion 374 of the valve to the port 322 and thence through the passageway 325 and port 327 to the right hand end of the lift cylinder. This moves the piston to the left, resulting in counterclockwise rotation of shaft 344 and, through the toggle linkage, results in raising of the platform.

The platform is provided at its rear end with an angular member 390 welded or otherwise suitably secured in transverse position thereacross. As the platform moves up into the raised position indicated in dotted lines, the vertical back of the angular member 390 engages the stop 303 and rotates the bell crank 302 in a counterclockwise direction. This, in turn, rotates the shaft 297 which, through the arm 296, moves the valve stem 293 to neutral position, resulting in closing the passageway 362 with respect to the passageway 365 and thus locks the mechanism in platform-raised position, the pressure in the lift cylinder being retained due to the fact that any exhaust from the passageway 365 is closed off in the neutral position of the valve.

When it is desired to lower the platform, the lift lever 44 is raised. This results in raising the rod 314 which, in turn, moves the rod 307 rearwardly and pulls on the valve crank 302 to rotate the shaft 297 in a counterclockwise direction. As a result, the valve is moved to the left in the bore 354, and the passageway 365 is opened to exhaust through the passageway 353. At the same time, the high pressure passageway 359 is placed in communication with the passageway 366 and oil under pressure is admitted therethrough into the left hand end of the lift cylinder, thus positively forcing the piston to the right to lower the platform.

It will also be noted that when the valve is in neutral position, the clutch mechanism, controlled by the shaft 388 and which will be described in more detail hereinafter, is returned to neutral position to declutch the pump from the driving gears in order to prevent building up of any oil pressure while the valve is in neutral position.

As the platform is lowered, the under surface of the horizontal portion of the angle member 390 comes into contact with the stop 304, rotating the valve crank 302 in a clockwise direction and thus moving the arm 296 in a corresponding direction to pull the valve stem 293 into neutral position. Thus it will be apparent that the upper and lower limits of movement of the platform will automatically result in moving the valve to neutral position and, simultaneously through the connection of the rod 307 to the bell crank, moving the lift lever to a corresponding neutral position, thereby declutching the pump from the drive shaft.

Referring now in detail to Figure 7 which illustrates the manner in which the pump shaft is driven from the transmission, the flywheel 95 of the transmission has the starting ring gear 108 at its outer periphery and has the smaller ring gear 109 riveted thereto as shown in Figure 4. There is provided a laterally offset housing 400 which is bolted to the side of the transmission housing as shown in Figure 3. The housing 400 is adapted to enclose the oil pump shaft 402 which extends parallel to the shafts 98, 150 and 165 and is disposed approximately in the same horizontal plane as the shaft 150. The end of

this housing is closed by the closure cap 403 bolted thereto which forms an end journal for the shaft 402. Adjacent its opposite end, the shaft 402 is journaled in a suitable ball-bearing assembly 404 carried by the front face of the housing 56 and also by a portion of the housing 400. A suitable gear 405 is mounted on thrust bearings 406 and 407 carried by the reduced portion 408 of the shaft 402, and the housing 400 is provided with an enlarged portion 409 enclosing this gear.

The gear 405 has a radially extending external tooth surface having meshing engagement with the gear 109 and driven thereby. Splined on the shaft 402 to the right of the gear 405 is a clutch thrust member 410 which is adapted to be moved to the left to produce clutching engagement of the clutch indicated generally at 412. This effects clutching of the shaft 402 to the gear 405 resulting in rotation of the shaft in accordance with the rate at which the gear is being driven by the gear 109. The clutch member 410 is actuated by means of the rock shaft 388 which projects into the housing 400 through the offset extension 413 and, within the housing, is connected to the clutch yoke 414 which is keyed to the shaft 388 and is rocked in a clockwise direction to move the clutch thrust member 410 into position to engage the clutch 412 for clutching the gear 405 to the shaft 402. At its end, the shaft 402 is provided with a slotted portion 415 which is journaled in the brass bushing 416 carried by the cap plate bolted to the front face of the housing 56 and the housing 400. The recessed portion 415 has engagement with the pump shaft 417 upon which is mounted a pump gear member of the usual type (not shown), having meshing engagement with the corresponding gear member mounted on a stub shaft whereby oil from the T connection 76 is drawn between the gear members and is expelled outwardly therefrom under pressure into the outlet connection 83. The pump housing, which is bolted to the housing 400 and is supported laterally of the crank case 88 of the engine, is indicated at 418.

By thus mounting the pump shaft directly on the side of the transmission housing, no misalignment is occasioned and the shaft can be held in its bearings in proper relation to the driving gear 109. A constantly meshed driving engagement is therefore provided, and the control clutch engages and disengages the oil pump.

Referring now in detail to Figures 8 to 10, inclusive, which show the lever control mounting for operating the pump clutch and lift valve, the lever 44 extends through the panel 15 and 55 through the frame plate 43 to the forward side of the panel. Mounted on the panel opposite the member 43 is the bracket-supporting member 425 which has forwardly extending ear portions 426 serving as supports for the shaft 384 which carries the bell crank comprising the arms 383 and 386.

Disposed above the plane of the shaft 384 is a second pair of journal supports 427 which support the shaft 315 for rotation. The shaft 315 serves as a pivot for the lever 44, and the lever 44 has the forwardly extending portion 380 which is connected through the pin 428 with the pair of toggle links 382 pivotally mounted on their opposite ends by the pin 429 carried by the crank arm 383.

Between the panel 15 and the shaft 315 and within the bracket 425, the lever 44 has a pivot pin 430 which is engaged by the yoke 432 connected to the shaft 314. At its upper end the

bracket 425 has a forwardly extending boss 433 forming a vertical slide for the pin 434 which extends therethrough and which, at its lower end, carries the fork arm 435, the arm 435 being 5 pressed into engagement about the shaft 315 by means of the spring 436 coiled about the pin 434. This normally tends to restore the lever 44 to its neutral position in which the pins 315, 428 and 429 are maintained in the same horizontal plane. When the lever is moved upwardly or downwardly about its pivot 315, the toggle knuckle 428 has corresponding movement. This 10 draws the arm 383 toward the pivot 315, resulting in rotation of the crank and producing a thrust on the rod 385 to actuate the pump clutch 412. At the same time, the shaft 314 is moved vertically in accordance with the movement of the lever 44 to move the control valve into position for allowing liquid under pressure to pass 15 into the lift cylinder. The bosses 438 formed on the lever 44 at the same time produce an upward thrust on the fork member 435, moving the pin 434 upwardly against the pressure of spring 436. This puts a bias on the lever 44 tending 20 to return it to neutral position.

When the platform engages either of the stops 302 or 303, this produces a corresponding movement of the rod 314 which pulls or pushes the lever 44 back to its neutral position, straightening 25 out the toggle between the links 382 and the arm 380 of the lever and rotating the lever 383 in a clockwise direction to produce disengagement of the pump clutch.

In order to hold the lever in either of its operative positions, I have provided on the end of the shaft 315 an arm 440 keyed thereto and having a spring-pressed ball detent 442 in the outer end thereof. Also, the bracket 425 is provided with a vertically extending flange 443 which, 30 at its upper end, has bolted thereto the arcuate plate 444 by means of the bolts 445. When the shaft 315, upon actuation of the lever 44, is rotated, the ball 442 is adapted to have selective detent engagement in the openings 446 or 447 35 formed in the plate 444. This holds the lever 44 in either of its operative positions against the pressure of return spring 436 and it is not until the impact of the platform upon the stop members has produced a thrust or tension of the shaft 314 that the ball 442 is pulled out of the 40 engaged opening a sufficient extent to allow the lever 44 to be returned to its neutral position under the action of spring 436.

It is therefore apparent that I have provided 45 a novel means of simultaneously engaging the pump clutch and opening the lift control valve with means automatically operated upon movement of the platform to either of its limiting positions for resetting the control lever to neutral position to simultaneously disengage the pump clutch and move the lift control valve to neutral position. This is of distinct importance in that the operator does not have to gauge the lowering or raising movement of the platform 50 but can move the lever to either of its operative positions and, when the platform has reached its opposite limiting position, the mechanism will be automatically returned to neutral position independently of the operator's presence or absence. This provides an effective safeguard against building up of fluid pressures when the platform has reached either of its limiting positions, and also in preventing excessive pressures 55 in the lift cylinder.

Considering now in detail the control mech-

anism for engaging and disengaging the main driving clutch and selecting operation of either forward or reverse drive, this mechanism is shown more clearly in Figures 11, 12 and 12A.

The lever 40, which extends outwardly through the frame plate 39 supported on the panel 15, passes inwardly within a bracket indicated generally at 450. This bracket is provided with vertically spaced forwardly extending portions 452 and 453 which serve as journals for supporting the segment 196 which is pivotally mounted thereon at its upper end by means of the pin 197 and, at its lower end, is frictionally clamped to the shaft 193 by means of the clamping bolt 454. The upper end of the shaft 193 is journaled in the projection 455 of the bracket.

The inner end of the lever 40 is bifurcated in a vertical direction having the two arm portions 455 and 456 which extend upon opposite sides of the member 202 having the extending trunnions or shaft portions 123 projecting through laterally spaced journal supports 456 bolted to the bracket 450. The member 202 serves as a spacing block by which the ends of the arms 455 and 456 are secured to the bolt or shaft member 200 which, at the same time, clamps these arms in such position that the lever 40 has vertical swinging movement about the shaft or trunnion portions 123 and has horizontal swinging movement about the bolt 200. The projecting portion 199 of the lower arm 456 is engaged in the slot 198 formed in the segment 196 and is limited in its upward movement in the slot by the stop 457 and in its lower movement by the stop 458, both formed integral with the segment. This limits the vertical swinging movement of the lever 40. The horizontal swinging movement of the lever 40 is controlled by the frame plate 39 which has the opening 460 formed therein, controlling sidewise or lateral swinging movement of the lever 40.

The lower portion of this opening is provided with inwardly tapering walls 462 so that when the lever is moved downwardly it will automatically be guided into neutral position by engagement with these tapered walls, neutral position corresponding to a position with the shaft 440 disposed at right angles to the trunnions 123. In this position, the shaft 193 is disposed in position so that the reversing clutch is intermediate the gears 166 and 169 and no transmission of torque to the shaft 165 can be effected. Also, in this position the crank 122, mounted at the projecting end of the trunnion 123, is in a position such that the rod 119 has moved the main clutch 102 into disengaged position so that the transmission is declutched from the engine.

Upon upward movement of the lever in a substantially straight line until its upper end is engaged between the arms 463 formed in the plate 39, the reversing clutch remains in neutral position, but the main clutch 102 connects the transmission to the engine to transmit driving torque to the transmission gears. However, no movement of the vehicle occurs since no power is transmitted to the shaft 165.

However, when the lever 40 is moved upwardly and at the same time is swung laterally so that it enters the notched portion 464 of the frame plate 39, the shaft 193 is rotated in a clockwise direction, resulting in engagement of the reversing clutch 177 with the gear 166 and, at the same time, engaging the main driving clutch whereby the vehicle moves forwardly.

When the lever 41 is raised into the opposite

notch 465 of the frame plate, the shaft 193 is rotated in a counterclockwise direction engaging the clutch 177 with the gear 169 and simultaneously engaging the clutch 102 whereby the 5 engine drives through the reverse gear train of the transmission to produce reverse movement of the vehicle.

Pivotedly mounted at 466 on the outer portion of the lever 40 is the throttle control lever 467 10 which has connected thereto the link 468 connected at its opposite end to the upper end of a crank arm 469. The crank arm 469 is mounted for rotation about the shaft 470 carried by the bracket 450, and the oppositely extending arm 15 portion 472 is connected to the throttle control rod 473 leading to the carburetor of the engine.

Thus when the operator grasps the handle 474 of the control lever 40, he at the same time controls, immediately adjacent thereto, the throttle 20 control lever 467 whereby, as the lever 474 is moved upwardly into either of the notches 464 or 465, the throttle control can be readily actuated to increase the speed of the engine in order to take up the inertia of starting. This provides an extremely advantageous control of 25 movement of the vehicle and speed of the engine, and insures that the lever 40, when moved out of driving position, will return to a neutral position so that if it is accidentally knocked upwardly, 30 it will move into position between the arms 463, and no driving motion will be imparted to the vehicle. Supported at the upper end of the bracket 450 is a horizontally extending boss member 475 which forms a suitable bearing guide 35 for the gear shift lever 38 which, at its inner end, is connected through the yoke 148 to the shift control rod 147. The lever 38 is provided intermediate its ends with an annular groove 476 which is adapted to have engagement with 40 the ball detent 477 when the lever is pulled outwardly into high speed position. This holds the lever in high speed position but allows its ready release when pressure is applied to the knob 478 threaded over the outer end of the gear shift 45 lever 38.

Considering now the means employed for steering the vehicle, I have disclosed in Figures 18 and 19 two diagrammatic illustrations of steering linkage. I find that for loads up to approximately 50 three tons, a four-wheel lift truck is desirable, while for greater load carrying capacities the number of wheels is preferably increased to six.

Considering first the four-wheel truck shown 55 diagrammatically in Figure 19, the rear wheels 19, as shown in more detail in Figure 3, have driving connection with the rear axle spindles and have their spindle mounting members 261 provided with flat vertically extending front faces 485 to which are bolted the crank arms 486, these 60 crank arms being curved forwardly and inwardly and terminating in bearing portions 487 pivotally mounted between the opposite arms of yokes 488 connected together by the tie rod 489. At the 65 rear of the right hand wheel spindle 261, there is also bolted the crank member 490 which, at its end 492, is connected to the drag link 493 shown in Figure 1 which extends under the operator's platform 18 and is connected to the crank arm 494 carried at the lower end of the vertically 70 extending steering shaft 495 which has its upper end 27 journaled in the bearing housing associated with the steering mechanism within the 75 housing 74. The shaft 495 forms a continuation

of the shaft 27 described in connection with Figures 1, 2 and 3.

The steering shaft 495 is also provided with a second crank arm 498 which, at its free end, is connected to the forwardly extending drag 5 link 499 which extends through the frame of the vehicle toward the front wheels 500. Each of the wheels 500 is mounted on a spindle bracket 502 which provides a dirigible mounting therefor, and the spindle portions 503 thereof have the 10 forwardly and outwardly extending crank arms 504 rigidly secured thereto to provide for dirigible mounting of these wheels for swinging movement about their vertical axes. The wheels themselves are supported on the forward portion of the frame members 505 shown in Figure 3 and the 15 crank arms 504 are tied together for conjoint rotation about the spindle pivots 503 by means of the drag link 506. The right hand wheel 500 also has rigidly secured to its spindle bracket 20 502 the crank arm 507 which has pivotal connection at its outer end, indicated at 508, with the forward end of the substantially longitudinally extending drag link 499.

In the operation of this steering linkage, rotation of the hand wheel 26 results in corresponding rotation of the shafts 27 and 495, and the vehicle is turned to the left when the shaft 495 is rotated in a clockwise direction. This results in corresponding rotation of the links 494 and 498. The crank 494 through the link 493 rotates the crank 490 to produce clockwise rotation of the crank arms 486, these two arms being tied together. The wheels 19 both simultaneously rotate in a clockwise direction tending to move the 35 rear end of the vehicle to the right. At the same time, however, the crank 498 through the link 499 rotates the arm 507 in a counterclockwise direction to produce corresponding counterclockwise rotation of the crank arms 504 40 which, being tied together by the link 506, produce corresponding rotation of the wheels 500 tending to rotate the front end of the vehicle to the left. The opposite turning effect imparted to the front and rear wheels under such circumstances allows the vehicle to turn in a relatively 45 short radius which is distinctly advantageous when the tractor is used in narrow aisles or passageways, such as in warehouses, manufacturing plants and the like. Opposite rotation of the 50 shaft 495 will impart an opposite turning effort to the wheels 19 and 500, causing the truck to make a right hand turn in the same manner. The drag links 493, 499, 489 and 506 are all adjustable in length so that the proper alignment 55 of the wheels can be obtained for normal driving operation.

Considering now the six-wheel truck and the showing in Figures 17 and 20 of the detailed manner in which the four wheels comprising 60 the front support for the truck are mounted, the respective pairs of wheels are indicated at 510 and 512. The wheels 510 and 512 on one side of the truck are each provided with spindle brackets 513 and 514 respectively, which are 65 supported for vertical pivotal movement on the ends 515 and 516, respectively, of a horizontally extending arm 517 which, at its center, is provided with the transversely extending shaft 519 70 which is supported in suitable bearings in the truck frame members 505 and which, in turn, supports the wheels 510 and 512 for dirigible movement about opposite ends thereof. In a similar manner the wheels 510 and 512 on the 75

opposite side of the vehicle are supported by a corresponding arm 517 carried at that side and pivoted intermediate its ends of the transverse shaft 519. The spindle bracket 513 of 5 the wheel 510 has an inwardly extending portion 520 rigid therewith which serves as a crank arm for rotating the wheel 510 about its spindle pivot. The crank arm 520 intermediate the spindle 513 and its outer end has pivotal connection 10 with the drag link 522 extending rearwardly through a suitable opening 523 in the transverse web between the frame members 505 at the forward end of the transmission and is extended rearwardly and has pivotal connection at 524 15 with the crank arm 498 carried by the shaft 495.

The rear wheels 19 of the truck are connected in the manner previously described through the crank 490 and drag link 493 with the arm 494 rigidly secured to the lower arm of the shaft 20 495. The wheels are interconnected by means 25 of the drag link 389 extending between the free ends of the crank arms 486.

Each of the pair of wheels 510 has rigid with 25 the spindle brackets 513 thereof, a rearwardly and inwardly extending crank arm 525, the outer ends of the crank arms 525 having pivotal connection to the drag link 526. Similarly, each of the wheels 512 has a forwardly and outwardly extending crank arm 527, the outer ends of these 30 crank arms being connected together by the drag link 528. In addition, the right hand wheel 512 has its spindle bracket 514 provided with a rigid extension 529 which extends through a suitable slot in the frame member 505 to a point 35 between the parallel frame members, and has pivotal connection, as indicated at 532, with a short drag link 533 which, at its opposite end 534, is pivotally connected to the free end of the crank 520 carried by the spindle bracket 513 of 40 the wheel 510. The frame member 505 is also slotted as indicated at 535 to receive the inwardly extending crank arm 520 and also to receive the drag link 526 connecting the rear pair of wheels 510.

45 In the operation of the steering mechanism shown in Figure 19, rotation of the shaft 495 in a clockwise direction results in corresponding rotation of the arms 494 and 498. This results in turning of the wheels 19 in a clockwise direction 50 through the crank arms 486 actuated by the crank arm 490 connected through link 493 with the arm 494.

The drag link 522, which extends longitudinally of the truck, is moved rearwardly resulting 55 in a counterclockwise rotation of the crank arm 520. This results in a corresponding counterclockwise rotation of the interconnection arms 525 rotating the wheels 510 in a counterclockwise direction or in a direction opposite to the turning 60 of the wheels 19. The crank 520, at its outer end, produces a rearward movement of the drag link 533 resulting in counterclockwise rotation of the crank 529 and corresponding simultaneous 65 rotation of the wheels 512.

65 Due to the fact that the drag link 522 is connected substantially to the middle of the crank 520, while the drag link 533 is connected to the end thereof, a greater rate of movement in the drag link 533 is produced than is produced in the 70 drag link 522. Thus, while the wheels 510 are rotated a predetermined distance about their spindle brackets 513, the wheels 512 are rotated through a greater angle due to this increased length of lever arm connected to the link 533. 75 This produces a substantially greater turning ef-

fect since the leading wheels 512 rotate through a substantial arc and are followed by rotation of the wheels 510 through a lesser arc to cause turning of the front end of the vehicle to the left, the wheels 19 being rotated in an opposite direction to cause the rear end of the truck to follow around in a relatively short radius whereby the turning radius of the truck is materially reduced over that of a truck in which only the front wheels are dirigibly mounted.

It will be apparent that reverse rotation of the cranks 494 and 498 will produce corresponding reverse rotation of the wheels 19, 510 and 512, swinging the vehicle abruptly to the right for a right hand turn.

It will thus be apparent that the hand wheel 26 can rotate all of the wheels of the truck so as to produce a relatively short turning radius with a minimum effort on the part of the operator since the reduction produced in the housings 74 20 and 496 reduces the force required to turn the shafts 27 and 495 so that the operator may, with facility, rotate the wheel and yet not be required to spin the wheel to an excessive extent in order to secure turning of the vehicle. The drag links 25 522, 526, 528 and 533 are all adjustable as to length so that proper alignment of the wheels can be obtained with respect to the wheels 19 and with respect to each other.

The mounting of the sets of wheels 510 and 30 512 on opposite ends of parallel arms 517 which are pivoted intermediate their ends, insures a substantial knee-action mounting of these wheels whereby no twisting stresses are imparted to the load-carrying platform 6 when the wheels are 35 passing over an uneven floor or roadsurface, since the wheels are free to move vertically about the transverse shaft 519 as separate units on each side of the vehicle. This eliminates any possibility of shifting of the load or uneven wear of 40 the tires on the wheels, and produces an efficient and positive support under the load-carrying platform.

Preferably, all of the wheels are provided with 45 solid rubber tires of the industrial type to reduce noise and to provide some resiliency of support of the vehicle on the road surface. Since 50 no braking effort is applied to the front wheels 500 or 510 and 512, the tires on these wheels may be made smooth, but preferably the tires 535 carried by the wheels 19 are provided with tread portions to increase their tractive effort and to prevent skidding.

In the use of the tractor for relatively heavy 55 loads of the order of five tons, it is desirable that the shaft 344 which carries the platform lifting arms 540 and 542 be subjected to a uniform lifting torque. For this reason it is preferable that the lifting or rotating effort applied to this shaft be equally apportioned between the opposite ends 60 thereof. I have therefore provided, as shown in Figure 20, a second gear segment 543 keyed to the shaft 344 and engaged by the rack portion 544 of the piston rod 545 extending into a second lift cylinder 546 carried at the left hand 65 side of the transmission housing 56 beneath the muffler 547 of the engine. The lift cylinder 546 is not provided with a control valve since the opposite ends of the lift cylinder are connected through suitable high pressure fluid transmitting connections 548 and 549 with the lift cylinder 9 so that upon introduction of pressure into either end of the lift cylinder 9, the fluid under 70 pressure will also be transmitted to the corresponding ends of the lift cylinder 546 to produce 75

movement of the piston therein and applying a rotative torque to the gear segment 543 as well as to the gear segment 343, thus producing an equalized torque upon the shaft 344. Similar connections (not shown) are provided between the rear ends of the lift cylinders 9 and 546, and therefore the mechanism is adapted for operation with only a single control valve 79 mounted on the lift cylinder 9.

10 From the foregoing description, it will be apparent that a number of important distinctive features of design and operation have been incorporated in the present construction of those disclosed in the aforesaid patents. These features may be briefly enumerated as follows:

The provision of an improved transmission design employing constantly meshed gears controlled by friction clutches of the multiple disc type whereby proper driving reduction is effected 20 between the engine and the rear axle spindles.

The provision of an oil pump which is journaled directly on the transmission housing to eliminate any possibility of misalignment and to provide a compact, easily controllable mechanism 25 which operates only when it is desired to raise or lower the load-carrying platform.

The provision of a novel type of transmission and throttle control member which may be read- 30 yly actuated by the operator and which simultaneously controls both the speed and direction of movement of the vehicle and has the additional feature of restoring the transmission to neutral position whenever the vehicle is stopped.

35 The provision of a novel lift control actuating means which simultaneously controls operation of the pump and the lift control valve and which is automatically returned to neutral position when the platform reaches either of its limiting positions.

40 The provision of a front wheel mounting arrangement which prevents the transmission of twisting stresses to the frame of the vehicle and prevents any possibility of load shifting, in connection with an improved type of steering control 45 that reduces the turning radius of the vehicle to an extent whereby it may be used with facility in narrow aisles and passageways.

It is apparent that these as well as other improved features of design and operation can be 50 modified, both in construction and arrangement of the constituent parts thereof and in their relation to the other portions of the operating mechanism of the vehicle, without departing from the basic underlying concepts of the present 55 invention, and I therefore do not intend to be limited to the exact details shown and described but only insofar as defined by the scope and spirit of the appended claims.

I claim:

60 1. In a lift truck, a lift cylinder having a control valve, a pump for supplying fluid under pressure to said cylinder and having a control clutch, a pivotally mounted control lever including a valve controlling lever connected to the lever 65 at one side of the pivot thereof and a clutch controlling lever having a toggle link connection to the lever on the opposite side of the lever pivot simultaneously operable to selectively open said valve and engage said clutch upon rotation 70 of said lever in opposite directions from a neutral position, spring means normally urging said lever to neutral position, and detent means for restraining said lever in actuated position.

75 2. A lift truck of the class described having a load-carrying platform, a cylinder including

a hydraulically actuated piston for raising and lowering said platform, a valve on said cylinder for controlling the admission of fluid under pressure to said cylinder, and means for operating said valve comprising a control lever pivoted for oscillating movement in opposite directions from a neutral position, lever means connected to said lever and including a bell crank pivotally mounted on one end of said cylinder, adjustable stop means on opposite ends of said bell crank adapted to be selectively engaged by said platform in its limiting positions, and a crank carried by said bell crank and connected to said valve for actuating the same in accordance with selected movement of said lever.

3. The combination, with a lift truck having a load-carrying platform at one end thereof and an engine at the opposite end, and hydraulically actuated means for raising and lowering said platform receiving fluid under pressure from a pump driven by said engine, of means for clutching said pump to said engine, means comprising a valve having a reciprocatory valve stem for controlling actuation of said hydraulic means, and a common control lever pivotally mounted 20 intermediate its ends and having valve stem actuating linkage connected thereto at one side of said pivot including a bell crank having its ends positioned in the path of travel of said platform, and a crank arm conjointly movable with 25 and pivoted co-axially of said bell crank connected to said valve stem, a bell crank pivoted adjacent said lever pivot and having one arm connected to the control lever on the opposite side of said pivot through a pair of toggle links, means connecting the other arm of said bell crank to said pump clutching means, whereby 30 rocking of said lever about said pivot in opposite directions from a neutral position produces unidirectional operation of said clutch means and 35 simultaneously selectively shifts said valve stem to opposite positions for effecting respective raising or lowering of said platform.

4. The combination, with a load carrying platform, a lift truck adapted to be selectively raised 45 and lowered by hydraulically operated means controlled by a remotely disposed lever, and a selecting valve for said hydraulically operated means, of a bell crank having normally extending arms, one of which is connected to said lever 50 and rocked thereby in opposite directions upon actuation of said lever, adjustable abutment means on each of said arms adapted to be selectively engaged by said platform in moving to its limiting positions for rocking said crank through 55 an arc sufficient to return said lever to a position intermediate its operating positions, and a crank pivoted co-axially of said bell crank and conjointly movable therewith and connected to said valve for returning said valve to an intermediate 60 position upon rocking of said bell crank by said platform.

5. The combination, with a load-carrying platform, a lift truck adapted to be selectively raised and lowered by hydraulically actuating means, 65 and a control lever for selectively controlling the admission of fluid to said actuating means, said control lever being pivotally mounted intermediate its ends for oscillating movement in opposite directions from a neutral position to effect raising or lowering of said platform, of an arched plate secured adjacent said lever pivot and having detent openings therein, a spring detent movable with said lever and engageable in said openings to restrain said lever in either of its oper- 70 75

- ating positions, a pair of abutments on the lever on opposite sides of the lever pivot, and forked spring pressed means bearing on said lever abutments for normally urging the same to neutral position.
6. The combination, with a lift truck having a load-carrying platform adapted to be raised and lowered by fluid pressure operated means under the control of a remotely disposed pivotally mounted control lever, said lever being rocked in one direction from a neutral position to effect raising of said platform and in the opposite direction to effect lowering thereof, of a pivotally mounted bell crank lever adjacent one end of said platform and having a vertical arm and a horizontal arm and operatively connected for rocking movement to said control lever, each of said arms having adjustable abutments selectively engageable by said end of said platform as it moves into either limiting position to rock said bell crank lever about its pivot for returning said control lever from its operated position to its neutral position.

7. The combination, with a lift cylinder, a piston therein, a valve mounted therein, a fluid pressure pump for delivering fluid to said valve, and a platform adapted to be raised and lowered by movement of said piston, of control means therefor comprising a control lever pivoted intermediate its ends, means connected to said lever on one side of said pivot for selectively actuating said valve upon movement of said lever in opposite directions to admit fluid under pressure to opposite ends of said cylinder, means having a toggle link connection to the lever on the opposite side of said pivot, said means being actuated by said lever independently of the direction of movement of the lever, and a bell crank in said selective actuating means having abutments at opposite ends thereof adapted to be respectively engaged by the bottom and back of said platform as it moves to its opposite limiting positions for returning said lever to neutral position.

ELMER J. DUNHAM.
